NORMAN B. WENK, OF WOODHAVEN, NEW YORK, ASSIGNOR TO AMERICAN CASTING & MANUFACTURING CORPORATION, OF BROOKLYN, NEW YORK, A CORPORATION OF NEW YORK

SEAL

Application filed October 11, 1930. Serial No. 488,000.

This invention relates, generally, to seals; and the invention has reference, more particularly, to improvements in lead seals of various kinds used to secure receptacles or other enclosures against unauthorized opening.

Heretofore, it has been common practice for post offices, banks, shippers and other users of lead seals to purchase such seals in the open market and to apply the same to the enclosures to be sealed. A standard seal press is used to deform or crimp the seal so that the tying cords or wires or other fastener means passing therethrough are gripped permanently by the seal. Frequently, the dies of the seal press are provided with lettering or other identifying marks, for example, the name and address of the user, which lettering is impressed upon the seals by the seal press at the time of crimping. However, in practice such standard seals do not provide adequate protection to the users thereof, because dishonest persons make it a practice to purchase standard lead seals and seal presses in the market and then have the seal press dies lettered or otherwise marked to conform with the lettering of the dies on a user's seal press desired to be dishonestly imitated. Such dishonest persons then cut the cord, wires or fastening means of seals on the user's bags or other enclosures and after pilfering from the latter, replace their own fictitious seals upon the enclosures, which fictitious seals are identical with the seals used by the user of the bag, thereby making it extremely difficult to detect the perpetrator of the larceny.

The principal object of the present invention is to provide a novel lead seal so formed as to provide an integral flap projecting from the seal body thereof, which flap is marked at the time of manufacturing the seal with certain identifying characters. Each novel lead seal is sold only to the user designated by such identifying characters. Thus, the flap of the seal may have a seal serial number depicted on one side thereof, and the name of the user depicted on the other side thereof. Since each seal is sold only to the user identified by

its flap, dishonest persons cannot purchase the same.

Another object of the present invention is to provide a novel lead seal which is of simple construction and easily manufactured and which is entirely reliable in use.

Other objects of this invention, not at this time more particularly enumerated, will be clearly understood from the following detailed description of the same.

The invention is clearly shown in the accompanying drawings, in which a cord seal for bags has been used to illustrate the principles of the invention.

Fig. 1 is a view in front elevation of the novel seal of this invention with the seal cord threaded therethrough preparatory to attaching the same to the neck of the bag to be sealed, the free end portions of the cord being broken away;

Fig. 2 is a view in rear elevation of the structure shown in Fig. 1;

Fig. 3 is a fragmentary view looking at the left side of the structure shown in Fig. 2;

Fig. 4 is a sectional view taken along line 4-4 of Fig. 1 and looking in the direction of the arrows;

Fig. 5 is a view similar to Fig. 1, but illustrates the appearance of the seal after the same has been crimped or deformed by a standard seal press;

Fig. 6 is a fragmentary view showing the seal pressed and secured to the neck of a bag, with the seal turned up to expose the rear surface thereof;

Fig. 7 is a view looking at the right side of the structure shown in Fig. 5;

Fig. 8 shows a bag having the contents thereof sealed by the novel seal of this invention; and

Fig. 9 shows the cord seal of Fig. 8 turned up to expose the rear surface thereof.

Similar characters of reference are employed in all of the above views to indicate corresponding parts.

Referring now to said drawings, the reference numeral 10 designates the body of the novel seal of this invention, the same being shown as of the cord type for sealing bags. Seal body 10 is preferably made of lead or

other soft metal or alloy and is of substantially square or rectangular shape, (although other shapes may be employed), and is of sufficient thickness to enable apertures 11 to be provided therein for receiving the sealing cord 12. Four such apertures 11 are illustrated as employed in the drawings and these apertures extend parallel to one another from the top to the bottom of the cord seal body. It will be noted that the cord 12 is so threaded 10 through the apertures 11 as to form a bight 13 below the bottom of the seal body. From the bight 13, the two runs of the cord 12 extend upwardly through the two outer apertures 11, are looped above the top of the cord seal body forming a bag neck receiving aperture 14, and then these runs extend downwardly through the two inner apertures 11. The free ends 20 of the cord runs project below the seal body and are adapted to receive a tag 15 in a manner to be described. A pointed pin 16 has the lower end portion of its shank fixed within a receiving recess provided in the seal body 10. Pin 16 projects inwardly from the seal body 10 and into 20 the bag neck receiving aperture 14.

According to the preferred construction, the seal body 10 is formed with an integral flap or tab 17 projecting outwardly at one side thereof. Flap or tab 17 is of lesser thickness than the seal body and is formed adjacent one edge of the front face 18 of the seal body 10. It will be understood, however, that this tab may as well be formed adjacent one edge of the rear face 19 of the seal, or 30 this flap may be positioned intermediate the planes of faces 18 and 19. At the time of fabricating the seal body 10, the flap 17 thereof is embossed or otherwise marked with certain identifying marks 21 and 22 on the front and rear sides thereof, respectively. Identifying mark 21 is illustrated as comprising a serial number designating the particular seal, whereas identifying mark 22 is 40 illustrated as consisting of the initials of the purchaser or user of the seal.

It is to be understood, of course, that the flap 17, having the type of identifying means shown thereon in the drawings, is merely 50 illustrative, and that other identifying information may be embossed or depicted on the flap in lieu of that given. The seal containing the identifying information shown on flap 17 of the drawings, would only be sold to the A. B. C. Co., and this seal would constitute seal No. A1000 of the seals purchased by this company. Dishonest persons therefore would be unable to purchase seals bearing this identifying means.

60 In use, to apply the seal, of the cord type illustrated, to the bag 23, the neck 24 of the bag is drawn tight or folded and the loops of the cord 12 forming the bag neck receiving aperture 14, are slipped over the neck of the bag and down as near as possible to the con-

tents thereof. The free ends 20 of the cord 12 are then pulled outwardly through the inner apertures 11, causing the loops of the cord surrounding the neck 24 to grip the neck. The ends 20 are pulled tightly and the pin 16 is pushed through the neck 24. The standard seal press is then applied to the seal body 10, and this press not only serves to crimp or deform the seal body into the form shown in Figs. 5 to 9, but also serves to pull the cords more tightly about the neck 24. The tab or flap 17 is substantially unaffected by the crimping of the seal body as shown in Figs. 5 to 9, so that the legend on this flap is readily readable after the crimping operation. The dies of the seal press may be provided with identifying or other marks if desired, which dies will serve to emboss such identifying marks upon the seals crimped in the press. For example, the seal press used in crimping the seal of the drawings was so marked as to cause the name of a company to be embossed on the front face 18, whereas the address of the company was embossed by the press on the rear face 19.

70 The free end portions 20 of the cord 12 are inserted through the aperture 25 in the tag 15 and these ends are knotted as shown at 26 in Fig. 9, so as to retain the tag 15. It will be apparent that tag 15 may or may not be used as desired since this tag merely serves to give a desired address of delivery or other information. With the cord seal as thus applied to the bag 23, it is impossible to open 75 the bag without deliberately destroying the bag or cutting the cord of the seal.

80 It will be apparent that when the novel seal of this invention is used on bags having a slip cord, such as post office mailing bags, the pointed pin 16 may be omitted, inasmuch as it is impossible to slide the slip cord off the neck of the bag. Since dishonest persons 85 cannot secure the lead seals of this invention provided with the correct identifying means on the flaps thereof, it will be impossible for such persons to remove seals from the bags 90 without detection.

95 While I have shown in the drawings, and have described above, a lead seal of the cord type, it will be obvious that the application 100 of the flap 17 may be made to practically all other specific forms of lead or deformable seals, regardless of the particular means by which the same is attached or connected to the enclosure to be sealed, and consequently, 105 in its broader aspects the invention is not to be deemed limited to the particular cord seal shown and described.

110 As many changes could be made in the above construction and many apparently 115 widely different embodiments of this invention could be made without departing from the scope thereof, it is intended that all matter contained in the above description or 120 shown in the accompanying drawings shall 125 130

be interpreted as illustrative and not in a limiting sense.

What is claimed:—

- A seal for sealing bags comprising, a flat seal body of substantially rectangular shape, said body having a plurality of spaced cord receiving apertures therein extending from the top to the bottom thereof, a sealing cord threaded through said apertures, said sealing cord having its central portion forming a bight at the bottom of said seal body, the cord runs at the sides of said bight extending upwardly through certain of said apertures and beyond the top of said seal body where said runs are looped to provide a bag neck receiving aperture, the free end portions of said cord extending downwardly through others of said apertures, and an identification flap formed upon one side of said seal body, said flap being of lesser thickness than the thickness of said seal body.

In testimony, that I claim the invention set forth above I have hereunto set my hand this 1st day of October, 1930.
